(57) **CLAIM**

The ornamental design for a one-piece toilet, as shown and described.

DESCRIPTION

FIG. 1 is a front perspective view of a preferred embodiment of a one-piece toilet showing our new design;

FIG. 2 is a top view of the one-piece toilet of FIG. 1;

FIG. 3 is a front view of the one-piece toilet of FIG. 1;

FIG. 4 is a left side view having a right side being a mirror image of the one-piece toilet of FIG. 1;

FIG. 5 is a rear view of the one-piece toilet of FIG. 1; and,

FIG. 6 is a bottom view of the one-piece toilet of FIG. 1.

The broken lines showing of a handle, hinges, bolt covers and portions of the bottom surface are for illustrative purposes only and forms no part of the claimed design.
